ENCLOSED PUMP HEAD WITH AIR-COOLED
ELECTRIC DRIVING MOTOR

Fenmore E. Dunn, Lawrenceburg, Ind., assignor,
by mesne assignments, to Byron Jackson Co.,
Inc., Lawrenceburg, Ind., a corporation of Indiana

Application March 19, 1949, Serial No. 82,340

2 Claims. (Cl. 103—87)

1

This invention relates to deep well pumps and more particularly to deep well pumps driven by an electric motor located at or adjacent ground level. In certain situations, as when the motor is located in a flood-proof housing or other relatively small enclosure, operation of the motor may be undesirably restricted because of the danger of overheating. It is an object of this invention, therefore, to provide for the cooling of a well-pump motor located in a closely confined space. Another object of the invention is to provide for the floodproofing of an electric motor driving a well pump. Still another object of the invention is to provide for a well-pump motor a floodproof casing or enclosure which will require no material alteration of the motor itself.

In carrying out the invention in its preferred form, I support the motor on a base which is connected to the pump column or well pipe through which water is elevated from the well by a pump located at or adjacent the foot of the column. The motor is disposed with its shaft vertical and connected to a pump driving shaft which extends downwardly through the pump column for operative connection to the pump. The motor which I prefer to employ incorporates a fan or blower by which air is circulated generally axially through the motor casing to prevent overheating of the motor, such air ordinarily entering the motor at the top and being discharged through one or more discharge ports at the bottom of the motor casing. For the purpose of cooling the air when the motor is located in a confined space, I mount adjacent the motor a heat-exchanging core having passages for cooling liquid and for the air to be cooled. The latter passages communicate with a shroud which surrounds the motor in the plane of the air-discharge ports so that air emerging from such ports is collected and forced through the heat-exchanging core to be cooled. The cooling fluid employed in the core is conveniently the water elevated by the pump, such water after passing through the core conveniently being returned to the well. For a flood-proof installation, the motor and heat-exchanging core are enclosed within a housing hermetically connected to the base.

The accompanying drawings illustrate the invention: Fig. 1 is a vertical section of a well head incorporating my invention; Fig. 2 is an elevation of the head in partial section; and Fig. 3 is a fragmental view similar to Fig. 1 but illustrating a modified construction.

In the arrangement illustrated in Figs. 1 and 2, there is secured to the top of the well casing 10

an annular collar or flange 11. The collar 11 is desirably welded to the top of the casing 10 in the field so as to effect a water-tight joint. Above the flange 11 I provide a base structure 5 comprising a central sleeve 12 provided with upper and lower flanges 13 and 14 desirably welded to or otherwise made integral with the sleeve 12. A gasket 15 is interposed between the flanges 14 and 11, and such flanges are secured together by means of an annular series of bolts 16. The pump column 18 through which water from the well is pumped upwardly is conveniently supported from the flange 14 of the base structure as by means of screws 19. In line with the pump column 18, the flange 14 is provided with an opening 20 through which the upwardly flowing water passes to the interior of the sleeve 12 to escape therefrom through a laterally arranged outlet nipple 21.

20 Centrally secured to the upper flange 13 of the base structure is a motor support 23 upon the upper end of which the pump driving motor 24 is mounted. The motor 24 is disposed with its shaft 25 arranged vertically and projecting 25 below the motor where it is connected by a coupling 26 to a pump shaft 27 extending downwardly through the well column 18 to the pump (not shown) located at the bottom of such well column. A stuffing box 28 surrounds the shaft 27 at or adjacent the upper base-flange 13 in order to prevent the upward escape of water from the sleeve 12 into the space above such base-flange.

30 As previously indicated, the motor 24 is of a type provided with means for circulating air through the motor casing in order to prevent overheating. In the particular motor illustrated, air enters the motor under the lip of a bell 30 at the upper end of the motor, is forced downwardly through the motor by any appropriate air-impelling elements mounted on the motor shaft, and is discharged from the motor casing through one or more outlet openings 31 at the lower end of the casing. In accordance with my invention, 40 the motor housing is surrounded in the plane of the openings 31 with a shroud 32 which serves to collect the air discharged from the openings 31 and to direct such air into a heat-exchanging core 33 supported in any convenient manner at one side of the motor. Conveniently, the shroud 45 32 is made of two sheet-metal parts joining each other at an axial plane of the motor and provided with flanges 34 which are secured together by bolts 35.

50 The core 33 may conveniently be of the type

employed in automobile radiators or automobile-body heaters, comprising upper and lower headers 37 and 38 interconnected by tubes 39 associated with which are heat-radiating fins 40 defining air passages through the core. One of the headers, conveniently the header 38, is connected to the upper end of the well column or to the outlet nipple 21 while the other header 37 is connected through the lower base-flange 14 with the interior of the well casing 10. In the particular arrangement illustrated in Figs. 1 and 2, connection of the header 38 with the outlet nipple 21 is effected through the medium of a hole extending through and appropriately located in the upper base-flange 13, opposite ends of such hole being provided respectively with fittings 42 and 43 connected by tubes 44 and 45 to the header 38 and outlet nipple 21. If desired, a valve 46 may be interposed in the tube 45 to control circulation through the core. A second hole in the upper base-flange 13 receives at its opposite ends fittings 48 and 49, the former being connected through a tube 50 with the upper core-header 37. Within the limits of the well casing 10, the lower base-flange 14 is provided with a hole which receives a fitting 51 connected to the fitting 49 by a tube 52. This method of effecting fluid-transmitting connections between points on opposite sides of the flange 13 is preferred to the use of a continuous conduit, as it simplifies assembly and disassembly and renders unnecessary the provision for a seal where such a conduit would pass through the flange.

To complete flood proofing of the motor, I may employ an inverted cup-like housing 55 large enough to surround the motor 24 and core 33 while resting on the flange 13. To secure the housing in position, it is provided at its lower end with an integral, external, annular flange 56 which is adapted to be attached to the flange 13 by an annular series of bolts 57. A gasket 58 interposed between the flanges 13 and 56 prevents ingress of water at the joint. If desired, the housing 55 may have a lateral extension 60 of smaller diameter through which access may be had, as for the purpose of adjusting a lubricating means 61, without the necessity of removing the entire housing from the base. If the extension 60 is employed, it is provided with a removable closure 62 held in place by any suitable means such as a removable collar 63. Conveniently, the closure 62 is a glass disk mounted between compressible gaskets 64 so that conditions within the housing may be observed.

With the housing 55 in place, the motor is effectively flood proofed. If the collar 61 is welded to or integral with the well casing 10, the well itself is also flood proof. If desired, the housing 55 may be provided with a valved fitting 66 through which air under pressure can be introduced into the housing when it is submerged in order to insure that any leakage which occurs will be an outward leakage of air rather than an inward leakage of water.

A modified form of the invention illustrated in Fig. 3 is essentially the same as that previously described except for the fact that it is adapted for use with a pump column 18' having an underground discharge (not shown). In this arrangement, the well column is suspended from the lower base-flange 14' as before, such base-flange being provided with a central opening 20' through which water may enter the base-sleeve 12'. In this instance, the conduit 45 and valve 46 through which water is supplied to the heat-

exchanger 33 are connected directly to the interior of the sleeve 12'. Conveniently, such connection is effected by making the sleeve 12' of larger diameter than the motor support 23 and by providing the upper base-flange 13 within the limits of the sleeve 12' with an opening 75 to which the valve 46 is connected. Water is conveyed from the heat-exchanger 33 through the tubes 50 and 52 as before; but in this instance, since the base is not directly associated with the well casing, the tube 52 merely extends downwardly through a hole in the flange 14' for connection therebelow to the well casing or some other disposal channel.

In each structure illustrated, current for operating the motor 24 is supplied thereto by a cable 70 which conveniently passes through the upper base-flange 13 (or 13') and has there associated with it an appropriate seal 71.

As will be obvious from the above description, in either of the modifications illustrated, air within the housing 55 circulates through the motor to cool it and then through the heat-exchanger 33 to be itself cooled. Heat removed from the air in the heat-exchanger 33 is transmitted to the water circulating therethrough, the heated water being returned to the well. Because of the continuous removal of the heat generated in operation of the motor 24, such motor can operate indefinitely without danger of overheating.

While my invention is primarily intended to permit flood proofing of a well-pump motor, certain advantages can be gained from its employment even if flood proofing is not desired. For example, the head without the housing 55 might be located in a small pit or other confined space in which normal air circulation is inadequate to insure cooling of the motor over long periods of operation. Obviously, the air-cooling means including the heat-exchanger 33 will function to cool air in the vicinity of the motor even in the absence of the housing 55.

I claim as my invention:

1. A head for a well having a casing and a well pump discharge column, flange secured in sealed relation to said casing, a base removably secured to said flange and including a liquid-tight sleeve in open communication with said pump discharge column and adapted to be filled with well water elevated through said column, a liquid-tight housing removably secured in sealed relation to said base, a motor supported from said base within said housing and operatively connected to a pump-shaft extending downwardly through said pump discharge column, said motor having openings for the inlet and discharge of cooling air, a heat-exchanging core within the housing, one of said openings communicating with the interior of said housing and the other with said core, said base having an opening communicating with said casing and means for conducting water from the interior of said sleeve to said core and for returning such water from the core to the opening in said base.

2. In combination with a well pump discharge column having a pump-shaft therein, a base at the upper end of said column, said base being provided with a liquid-tight chamber having open communication with the interior of said discharge column to be filled with water elevated therethrough, said chamber having an upper wall provided with an opening through and above which said shaft extends, sealing means for

preventing the escape of water through said opening about said shaft, said base including an outwardly extending flange near its upper end, an electric motor mounted on said base and having a shaft above and coaxial with said pump shaft, coupling means for interconnecting said two shafts, said motor having inlet and outlet openings for cooling air, a heat-exchanging core, means for collecting heated air discharged from said outlet openings and conveying it to said core, 10 a water-supply conduit having one end thereof in open communication with said chamber and having its other end in open communication with said core to provide a passage for flow of well water from said chamber to the core, a water- 15

return conduit connected to said core, and an open-bottomed, liquid-tight housing enclosing the motor and core and secured to said flange in sealed relation.
